UNITED STATES PATENT OFFICE.

FORREST G. PURINTON, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON-FEEDING MECHANISM.

Application filed March 16, 1925. Serial No. 15,794.

To all whom it may concern:

Be it known that I, FORREST G. PURINTON, a citizen of the United States, residing at Waterbury, in the county of New Haven and State of Connecticut, have invented certain new and useful Improvements in Button-Feeding Mechanisms, of which the following is a specification.

My invention relates to new and useful improvements in button feeding mechanisms for automatic button attaching machines, and more particularly to the button magazine or hopper and the arrangement of the chute cooperating with the hopper.

As is well known to those skilled in the art, automatic button attaching machines comprise mechanism working in two separate zones, that is, there is a magazine or hopper and an escapement mechanism for the button heads, and likewise a separate hopper and magazine for the tacks or staples. There is also a plunger for forcing the tacks through the button heads, the several parts being synchronized so that there will be a tack for every button head.

The magazines for both the tacks and button heads are rotatable so that the respective button parts may be poured into these magazines from which they will automatically feed, and be released in their respective chutes to the plunger.

It is practically impossible to prevent a jam at times of the button heads in the magazine or the chute leading therefrom, due to the irregularities in the button heads, damaged button heads, or other causes, and in the numerous types of button magazines now in use, when such a jam occurs, it is necessary to disassemble several of the parts to thus relieve the jam.

One of the principle objects of the present invention therefore, is to so construct a hopper or magazine for the button heads, which is arranged to be swung upwardly or tilted and thus disclose the chute, so that, if for any reason the button or buttons become jammed, either in the outlet from the hopper, or from the chute, they may be quickly removed as with the hopper swung back or upwardly, the offending buttons may be easily perceived and readily reached by the operator.

Still another object of the invention is to so construct the hopper with relation to the chute that the hopper may be tilted upwardly if the occasion arises and at the same time the tilting or elevating of the chute will in no way interfere with the means for revolving the hopper.

Another object of the invention is to construct a feeding mechanism for button heads which comprises a hopper and chute, and to so arrange the hopper casing and its cooperating parts that the hopper may be slowly but continuously rotated by a belt which extends downwardly to the driving means of the machine proper, thus doing away with the more expensive ratchet mechanism which is now employed on button attaching machines, such a ratchet mechanism being shown in a patent granted on December 2, 1913, Number 1,079,968.

Still another object of the invention is to provide a button feeding mechanism comprising a hopper and chute and a supporting plate for the hopper and chute, while secured to the upper end of the plate there is an arm in which there is formed a bearing, and in which bearing is mounted a plate which comprises a bottom for the hopper. This plate may be quickly and easily raised to thereby raise the hopper in its entirety, to thus relieve any jam that might have occurred in the chute or the entrance thereto.

Still another object of the invention is to provide a bottom plate for the hopper, which is, as before mentioned, tilttable and to which is secured an arm having mounted on its opposite sides two small sheaves or pulleys over which there is designed to pass a belt to be driven by the driving means of the button attaching machine. This belt is designed to also rotate the casing of the hopper, the sheaves and hopper being so arranged that when the latter is raised or tilted, the pivotal axes of the sheaves will not material change, thus doing away with the necessity of in any way disturbing the belt when it is desired to raise the hopper to pick out an offending button.

Still another object of the invention is to provide a hopper casing, a chute and a plate, the hopper casing slidingly fitting on

the plate so that the hopper casing may be bodily removed if desired, as well as being capable of simply a tilting action to pick out an offending button.

Still another object of the invention is to provide a button feeding mechanism comprising a hopper in the form of a casing which may be placed on a plate which forms the bottom of the hopper, the plate being 10 tiltable with relation to the chute, the hopper casing being capable of a slow but continuous rotation, and so arrange the various parts that they may be quickly and readily interchanged on a button attaching 15 machine, so that if for any reason, one part should become injured or damaged in use, it may be quickly removed.

Still another object of the invention is to provide a non-rotatable plate which 20 forms the bottom of a hopper and to provide this plate with an opening and dished portion so that a chute may protrude therethrough, also to so arrange the opening in the plate and a peripheral edge of the plate 25 that those buttons which lie face downwardly will be guided and other buttons will drop from the entrance of the chute to the bottom of the hopper, thus providing 30 a clear opening for the properly faced buttons.

Still another object of the invention is to provide a hopper casing which is designed 35 to slip over a platform formed on a non-rotatable plate and to have the platform project slightly above the bottom of the casing to thus form a small ledge for supporting the buttons as they are rotated within the hopper casing, and to deflect a portion 40 of the ledge, near an opening formed in the bottom plate in which opening registers a chute, so that a properly faced button will be guided towards the mouth of the chute and passed into the chute after the button 45 leaves the influence of radial walls formed in the hopper casing.

Still another object of the invention is to provide a hopper having a non-rotatable 50 hopper bottom having a dished portion at its upper edge through which is cut an opening for the reception of the upper end of the chute, the upper end of the chute and the plate arranged to guide a properly faced button into the chute and to permit other buttons to quickly pass from the entrance to the bottom of the casing, thus 55 always providing an obstructed passage-way into the chute.

Still other objects of the invention are 60 to provide a button feeding mechanism for automatic button attaching machines which will be extremely efficient in service, easily constructed, quickly and readily assembled and comprising but a minimum number of parts, and therefore relatively cheap to 65 manufacture.

Still another object of the invention is to provide a hopper with a wide opening where the buttons pass to the chute thus facilitating the charging of the button and the removal of scrap. Furthermore a wide 70 opening reduces the jams which might otherwise occur directly at the mouth of the chute and permits a jam to be removed without stopping the hopper.

Still other objects of the invention are to 75 provide a button feeding mechanism which is continuously rotated and extremely efficient in service.

It will be understood that when I speak of a button feeding mechanism throughout 80 the specification and claims, I contemplate a feeding mechanism for button heads, such as pants and shirt buttons, thin metallic shells such as used for making backs and fronts for overall buttons, sew-on buttons 85 and discs. Furthermore, the feeding mechanism may be used for eyelets or fasteners without changing or departing from the spirit of the invention.

With these and other objects in view, the 90 invention consists in certain new and novel arrangements and combination of parts, as will be hereinafter more fully described and pointed out in the claims.

Referring now to the drawings showing 95 a preferred embodiment of my invention,

Fig. 1 is a view in side elevation of my improved button feeding mechanism, showing the manner in which the hopper is rotated, the casing of the hopper being also 100 shown in dotted lines to show how it may be bodily removed, and the oscillating lever for the button attaching machine being shown in dotted line.

Fig. 2 is a sectional view of the hopper 105 taken on line 2-2 of Fig. 1.

Fig. 3 is a sectional view, taken on line 3-3 of Fig. 1.

Fig. 4 is a sectional view, taken on line 4-4 of Figure 1.

Fig. 5 is a longitudinal sectional view taken on line 5-5 of Fig. 6 looking in the direction of the arrows, the dotted lines showing how the hopper may be lifted or tilted to remove an obstructing button.

Fig. 6 is a top plan view of the button feeding mechanism, parts being broken away for the sake of clearness.

Fig. 7 is a detailed view of the escape- 120 ment.

Fig. 8 is a sectional view taken on line 8-8 of Fig. 6.

Fig. 9 is a perspective of the feeding mechanism showing the hopper swung upwardly.

Fig. 10 is a fragmentary perspective of the bottom plate of the hopper, the plate being elevated to show the relative positions of the upper end of the chute and the opening in the bottom plate.

Fig. 11 is a perspective of the upper end of the chute, in a reversed position.

Fig. 12 is a detailed perspective of the upper end of the chute and taken from the same relative position as Fig. 11.

Fig. 13 is a perspective from the under side of the small plate shown in Fig. 10.

Referring now more particularly to the several views, there is shown a supporting arm 1 provided with the holes 2, so that this arm may be attached to a support of a button attaching machine (not shown). Extending from the upper end of the arm 1, and preferably formed integrally therewith 15 and extending at right angles thereto, is the plate 3 forming a support for a metal trough 4, the upper end of the trough merging with the curved arm 5 having the bearing 6 formed therein. This trough, arm 20 and bearing are all formed of one solid piece of steel or cast iron, and held on the plate 3 by means of the bolts 7. The side walls 8 of the trough extending out beyond the sides of the arm 5, may be clearly seen 25 in Fig. 2. The side walls 8 are similar throughout their length with the exception of the upper end of one side wall where a portion 9 is cut out, as may be seen in Fig. 11, so that the upstanding wall 10 of this cutout portion is in alignment with a wall 11, (see Fig. 10), the latter wall being formed by dishing out a portion 12 in the bottom of a plate 13 which forms the bottom of the hopper, which latter will be shortly 30 described.

The metal trough 4, which is a part of the arm 5, has its upper end slightly dished as at 14 for the sake of clearance, so that when the metal plate 13 is in its normal position, the end of the trough will not interfere with the pivotal axis of the plate.

Fitting snugly within the trough and at its upper end, is a small section 15 of a button chute, and registering with this small section 15 and lying within the trough is a longer chute section 16, (see Figs. 5, 6 and 9) this section being in spiral formation near its lower end as at 17 so that a button head 18, as it passes down the chute will invert itself as is the general practice in chutes for button attaching machines.

The chute 16 is cut away at its opposite sides as at 16' for the reception of the jaws of the escapement mechanism 19, this escapement mechanism being shown and described in a patent granted October 26, 1915, Number 1,157,743, and in passing it might be mentioned that this escapement oscillates across the chute by contacting with the lug 53' on an oscillating lever 53 shown in dotted lines in Fig. 1.

The section 16 of the chute is secured in the trough 4 and as before mentioned registers with the section 15, the upper end of the section 15 having its side walls 20 and

21 arranged differently at their ends as shown in Fig. 12, so that a button head, when it passes onto the bottom 22 of the chute section 15, will contact with the edge 23 of the side wall 21 and will have moved 70 slightly downwardly before the opposite edge of the button strikes the side wall 20. In other words, the upper end of this chute section 15 is so arranged that as the hopper is rotated and the button swipes or revolves 75 onto the bottom wall 22, it will tend to drop as it will be rolled over the edge 23 until it completely enters the chute and its side will not impinge or strike the side wall 20 until it has moved partly down the chute. 80

The side walls of the chute section 15 are undercut to form the inwardly extending rims or flanges 24 and the one, the longer of the two, is slightly beveled on its top surface as at 25, corresponding to a small 85 beveled surface 26 formed in the side wall 8 of the trough. The bottom plate 13 is provided with an opening 27, which will be shortly described in detail, to permit the upper end of the section 15 to extend there-through when the hopper is in its normal position, so that the buttons may pass into the chute, and the small beveled surfaces 25', 26 permit a small auxiliary plate 28 90 to be fastened flush on the bottom plate to thus cover the opening 27 in the bottom plate and to help guide a properly positioned button into the chute. This plate also helps in the rejection of buttons that are lying with their hubs downwardly, or ones that have missed the mouth of the chute.

This opening 27 in the plate 13 and the walls adjacent the opening will now be described more in detail, as the opening is 105 the mouth or exit for the button heads into the chute and also receives the upper end of the chute.

As before mentioned, this bottom plate is 110 dished as at 12, this dished portion occurring in the upper right hand corner of the plate, as may be seen in Fig. 10, it being remembered that Fig. 10 shows the plate in its reversed or transposed position. This dished portion extends across the opposite sides of the opening 27, which opening, as heretofore mentioned, is of sufficient size to permit the plate 13 to be swung downwardly over the projecting end of the chute section 15. By starting this dished portion at a point in the periphery of the plate 13, a small guiding ledge or wall 29 is formed, and as a button contacts with this wall 29, as will be herein-after mentioned, the button will be guided 115 into the mouth of the chute. 120

The plate 28 is screwed to the plate 13 and is slightly undercut at one corner 29' and is arranged to slightly overlie the wall or ledge 29 so that this corner will project slightly 130 over the button head and tending to guide

it as it rolls into the chute. The plate is also slightly cut out as at 30, to allow the hub of the button to pass under the plate as the button registers in the chute, and 5 there is a slightly beveled corner, as at 31, on the upper surface of the plate to prevent jams which would otherwise occur between the inside corners of the walls which form the button pockets in the annular ring and 10 the shoulder of the plate 28.

Referring now more in particular to the plate 13, it will be seen that it is circular in outline and is provided with the flange 32, thus forming a seat for a ring 33 secured in 15 the bottom of a hopper casing 34. The plate 13 extends slightly above the upper surface of the ring 33, as may be seen in Fig. 2, to form a ledge for the support of properly facing buttons. Formed integral with this 20 plate 13 are the two arms 35 which merge with a housing in the form of a trough 36, as may be clearly seen in Fig. 9.

In the upper ends of the arm 35 are formed the bearings 37 to pivotally engage a 25 pintle 38, this pintle also passing through the bearing 6 formed in the upper end of the arm 5. A set screw 39 passes through the bearing 6 and locks with the pintle 38, but the arms 35 are free to swing on the pintle 38. 30 The width of the housing 36 is slightly greater than the width of the trough 4 so that when this housing 36 is swung downwardly to its normal position by a movement of the plate 13, it will box-in the trough 4 as may 35 be seen in Fig. 3. This housing 36 has the central longitudinally extending groove 40 formed in its upper under surface and is cut out slightly as at 41 (Fig. 10) to permit the stem or shank of the buttons to pass 40 downwardly through the plate.

The length of the trough 4 and the length 45 of the housing 36 is such that their lower ends are flush as may be seen in Fig. 6. To one side of the housing 36 is secured a handle 42 so that when it is desired to raise the 50 hopper and the plate and casing, it is only necessary to lift up the handle 42 and makes it then possible to force an offending button from either of the chute sections or from the entrance to the chute at the opening 27 in the plate 13.

Referring now to the manner and arrangement for imparting a rotary motion to the hopper casing, I have shown a plate 43 fastened to the under surface of the plate 13, by means of the screws 44, while the outer end of this plate 43 is provided with two up-standing opposite lugs or flanges 45 in each of which is mounted a small sheave or pulley 46, the position of these sheaves being such 60 that a belt 47 may pass over them and around and over a small belt pulley 48 driven by the drive wheel 49, this drive wheel 49 being driven by a belt 50. I have shown 65 an eccentric 51 to which in turn is secured

a connecting rod 52 extending to the oscillating lever 53 which operates the button attaching machine (not shown).

After the belt 47 passes over the sheave 46, it fits within a groove 54 formed in the ring 33, which, it will be remembered is in the hopper casing.

Thus it will be seen that as the main drive wheel 49 is rotated, the hopper casing 34 will also be rotated, and at the same time 75 the axes of the sheaves 46 are such that the hopper may be elevated to remove an offending button in the chute, without in any way seriously affecting the driving or rotating of the hopper casing.

Now, just a word as to the ring 33. As before mentioned, it is provided on its outer periphery with the groove 54, while on its upper surface there are provided a plurality of pockets which are formed by so cutting the ring that the small beveled walls 55 are left remaining, which walls extend towards the inner circumference of the ring 33 and their rear surfaces are flush with, and contact 80 against the casing of the hopper 35.

The ring 33 is slightly beveled from its outer periphery to its inner periphery, as may be seen in Fig. 5, and this beveled surface, together with the angular position of the rotating axis of the hopper casing, causes the buttons, which arrange themselves in the pockets formed by the side walls 55, to slide from the pockets as they approach the vertical into the chute from which they 90 are passed one by one by the escapement.

It will be remembered that the plate 13 extends slightly above the inner surface of the ring 33 forming a small ledge on which the buttons rest as they approach the vertical, as shown in Fig. 6, this arrangement being shown in the application filed by me on 95 August 1, 1924, bearing Serial Number 729,564.

By forming the hopper casing and ring as shown, I have made it possible to not only tilt or lift the hopper by tilting the plate 13, but I have also made it possible to quickly remove the hopper casing which carries the ring, as it simply rests on the plate 13, the flange 32 forming the seat.

The operation of the device is extremely simple and presupposing that there are a number of button heads in the hopper, as the casing 34 is rotated by the belt 47, a button head, as it approaches the vertical, riding on the small ledge on the plate 13 projecting above the ring, will drop or slide from one of its little pockets as clearly shown in Fig. 6, and impinge on the wall 29 and travel therealong, and as it leaves the influence of one of its walls 55 of its pocket, it will pass onto the end of the chute, which it will be remembered extends through the opening in the bottom plate and pass down the two sections of the chute to the escape- 110 115 120 123 128 130

ment 19, where it will be liberated in due course.

Other button heads which are not properly positioned, or have not been carried upwardly on the small ledge will slip back to the bottom of the rotating hopper and thus keep the entrance to the chute free.

Now, due to the irregularities in some of the button heads, should a button at any time 10 become jammed, either in the chute, or the mouth of the chute, it is simply necessary to lift the handle 42 and thus raise the plate and hopper casing to the position shown in Fig. 9 and with a pointed instrument, such as 15 a screw-driver, the offending button may be quickly and easily removed from the top of the chute and the hopper again lowered to its regular position.

This may be done without affecting the 20 rotating means of the hopper, that is, without taking any of the machine apart or removing the belt, as the axes for the belt move with the swinging or tilting of the hopper; thus overcoming the delay which 25 would otherwise be caused by a jammed button.

Furthermore, the entire hopper casing may be quickly removed when so desired.

From the foregoing it will be seen that 30 I have provided a feeding mechanism for automatic button attaching machines which is simple in construction, readily assembled and extremely efficient in action, and by providing a tilttable hopper and a driving mechanism, as shown, offending buttons may be 35 quickly removed without delaying the speed of the machine.

Again, by forming the several parts as above described, it is a simple matter to substitute any parts should they become damaged or worn in service.

Many slight changes might be made in the hopper casing and ring, or the arrangement of the chute, or the position of the sheaves, or the rotating mechanism for the hopper, without in any way departing from the spirit and scope of the invention.

Having thus described my invention, what I claim as new and desire to secure by Letters Patent is:—

1. A feeding mechanism for button attaching machines comprising a chute, a rotatable hopper casing, a non-rotatable bottom plate supporting the casing and provided with an opening for alignment with said chute, and means for pivotally mounting said plate so that the hopper casing and plate may be elevated to remove an offending bottom from the chute.

2. A feeding mechanism for button attaching machines comprising a chute, a rotatable hopper casing, a non-rotatable bottom plate for the casing provided with an opening for the reception of the upper end of said chute, said plate supporting said

casing, and means for pivotally mounting said plate so that the hopper casing and plate may be elevated to remove an offending button from the chute and hopper.

3. A feeding mechanism for a button attaching machine comprising a chute, a rotatable hopper casing, a non-rotatable bottom plate supporting the hopper casing provided with an opening for the reception of the upper end of said chute, means engaging and supporting the chute, and pivotal mounting means for said plate secured to said last means so that the plate may be elevated to afford free access to the chute.

4. A feeding mechanism for a button attaching machine comprising a chute, a rotatable hopper casing, a non-rotatable bottom plate supporting the casing, said casing being bodily removable from the plate, the said bottom plate provided with an opening for the upper end of said chute, and pivotal mounting means for said plate so that the plate may be elevated to afford free access to the chute.

5. A feeding mechanism for a button attaching machine comprising a chute, a rotatable hopper casing having a bottom provided with a large central aperture, a non-rotatable bottom plate fitting within the said aperture in the casing, the said bottom plate provided with an opening for the reception of the upper end of said chute, and pivotal mounting means for said plate so that the plate and hopper casing may be swung upwardly to afford free access to the chute.

6. A feeding mechanism for button attaching machines comprising a chute, a rotatable hopper casing having a ring in the bottom thereof divided into a plurality of compartments, a plate fitting within said ring and supporting said casing and having an opening therein to receive the upper end of the chute, and means for pivotally mounting said plate beyond the upper end of said chute so that the plate and hopper casing may be lifted upwardly to afford free access to the chute.

7. A feeding mechanism for button attaching machines, comprising a chute, a rotatable hopper casing having a ring in the bottom thereof, radial walls extended from points near the inner periphery of the ring to the outer periphery of the ring to provide a plurality of button compartments, and a plate pivotally mounted above the upper end of the chute and extending over said chute and the ring of the hopper casing fitting on said plate, said plate also provided with an opening for the reception of the upper end of said chute, and said plate adapted to be tilted to afford free access to the chute.

8. A feeding mechanism for button attaching machines comprising a chute, a

6

rotatable hopper casing having a ring in the bottom thereof, radial walls extending from near the inner periphery of the ring to the outer periphery of the ring to provide a plurality of button compartments, said ring having a tapered upper surface and provided with a groove on its outer periphery, and a plate mounted in pivotal relation to said chute and provided with an opening for the reception of the upper end of said chute and adapted to be swung upwardly to provide free access to the chute.

9. A feeding mechanism for button attaching machines comprising a chute, a rotatable hopper casing having a ring at the bottom thereof, said ring having a plurality of compartments formed thereon, the said compartments being open at their bottom, a plate having a raised portion pivotally mounted with relation to said chute for supporting the casing, the inner wall of said ring engaging the raised portion of said plate, the said plate provided with an opening to register with said chute, and means for rotating the ring and thus the hopper casing acting in substantially the plane of the pivotal axis of the plate so that said hopper casing and plate may be tilted upwardly without affecting the rotatable means of said hopper.

10. A feeding mechanism for button attaching machines comprising a chute, a rotatable hopper and casing, an inwardly extending annular ring, a plate pivotally mounted with relation to the chute and having a raised central portion to tightly fit within the ring of the hopper casing, said plate having an opening registering with said chute, an arm extending from said plate, guiding means on said arm on its outer end for a belt, the axes of the guiding means being substantially in the same horizontal plane as the pivotal axis of the plate, said hopper provided with a peripheral groove for the reception of the belt, and a belt disposed in said peripheral groove and over said guiding means for rotating the hopper, said hopper thereby being arranged to be tilted upwardly to remove an offending button without affecting the rotatable driving means for the hopper.

11. A feeding mechanism for button attaching machines comprising a chute, a rotatable hopper casing having a metal bottom wall in the form of a ring, a plate pivotally mounted with relation to the chute, said plate being provided with a raised surface adapted to fit within the ring of the hopper casing, the said plate provided with an opening to receive the upper end of the chute, the top surface of the upper end of the plate lying in the same plane with the top end of the chute, and the top surface of the lower end of the plate being in a plane above that of the chute, and means

for rotating the hopper acting in a plane substantially parallel with the pivotal axis of the plate to thereby allow the hopper to be raised without affecting the rotatable means for the hopper.

12. A feeding mechanism for button attaching machines comprising an arm having a bearing formed in its upper end, a chute supported in the lower portion of said arm, a bottom plate pivotally mounted in the bearing of said arm and normally extending downwardly over said chute and at an angle thereto, said plate provided with an opening to receive the upper end of said chute, a hopper casing mounted on said plate and supported thereby, a driving belt for said casing, and guiding means for the driving belt associated with the plate and disposed in a plane substantially parallel to that of the pivotal axis of the plate to allow the hopper to be raised without materially changing the position of the guiding means.

13. A feeding mechanism for button attaching machines comprising a curved arm and a trough, forming a part of said arm, a bearing formed in the upper end of said arm, a pintle extending through said bearing, a plate having a similarly curved arm formed thereon and pivotally mounted on said pintle, a chute fitting within said trough and the plate provided with an opening to receive the upper end of said chute, and a rotatable hopper casing mounted on said plate, said plate and hopper casing adapted to be swung upwardly manually to provide free access to said chute.

14. A feeding mechanism for button attaching machines comprising an arm curved at its upper end and in the form of a trough at its lower end, a bearing formed at the upper end of said arm, a pintle in said bearing, a plate having arms formed on its under surfaces and their upper ends mounted on said pintle, the lower ends of the said last mentioned arms and a portion of the plate arranged to form a casing to enclose said trough when the plate is in its normal position, a chute tightly fitting within said trough, the plate provided with an opening to receive the upper end of said chute, and a rotatable hopper casing mounted on said plate, said plate adapted to be tilted upwardly to thereby swing the casing and plate away from said chute to thereby provide free access to said chute.

15. A feeding mechanism for button attaching machines comprising an arm curved at its upper end and having its remaining portion shaped to form a trough, a bearing formed in the upper end of the arm, a pintle within said bearing, a plate having spaced arms formed on its under surface and the arms and a part of the plate shaped to form a housing to encase the trough when the plate is in its normal position, said plate

provided with an opening, a chute within said trough and extending beyond the upper end of said trough and into the opening of said plate, and a rotatable hopper casing 5 mounted on said plate, said plate adapted to be tilted upwardly to thereby remove the casing from the trough and provide free access to the chute.

16. In a feeding mechanism for button attaching machines a support, a trough secured to said support, an arm extending from the trough having a bearing formed therein, a pintle within said bearing, a plate having arms thereon pivotally mounted on said pintle, a box-like casing merging with said arms on the plate and adapted to enclose the said trough, the plate provided with an opening, a chute within the trough, the upper end of the chute registering with the opening in said plate, and a rotatable hopper casing on said plate, said plate adapted to be swung upwardly to afford free access to the chute.

17. In a feeding mechanism for button attaching machines, a support, a trough secured to said support, an arm extending from the trough having a bearing formed therein, a pintle within said bearing, a plate having means thereon for engaging the pintle, a box-like casing open at its bottom formed on the under surface of the plate adapted to enclose the trough and provided with an opening, a chute within the trough, the upper end of the chute registering with the opening in said plate, and a rotatable hopper casing on said plate, said plate adapted to be swung upwardly to afford free access to the chute.

18. A feeding mechanism for button attaching machines comprising a support, a trough secured thereto, an arm extending from said support having a bearing formed therein, a hopper comprising a non-rotatable plate and a rotatable casing, the plate pivotally secured in said bearing and provided with an opening therein, a chute fitting within said trough and extending within said opening, said chute extending beyond the upper end of the trough, and one of the side walls of the chute being greater in length than its opposite side walls so that a button dropping from the hopper into the chute will strike against one of the side walls before striking against the other.

19. In a button feeding machine a trough, a chute within the trough, a plate mounted in hinged relation to the chute, said plate provided with an opening for the reception of the upper end of the chute, a rotatable hopper casing on the plate, the side walls of the chute terminating a short distance from the upper end of the chute, and a wall in the upper edge of the plate for guiding a button into the chute as it approaches the same, said plate and hopper casing capable

of being tilted upwardly to provide free access to the chute.

20. In a button feeding machine a trough, a chute within the trough, a plate mounted in hinged relation to the trough and having 70 a casing for enclosing the chute and trough, the said plate provided with an opening for the reception of the upper end of the chute, a rotatable hopper casing supported by said plate, the side walls of the chute terminating a short distance from the end of the chute and one of the side walls being longer than the other, and means in the form of a wall at one edge of the opening in the plate for guiding the button against the end of 80 the longer of the said side walls of the chute, so that the buttons will drop slightly before impinging against the opposite side wall of the casing, said plate adapted to be swung upwardly to thereby provide free access to 85 the upper end of the chute.

21. A feeding mechanism for the button attaching machines comprising a chute, a hopper in pivotal relation therewith, the hopper comprising a rotatable casing and a 90 non-rotatable plate provided with an opening for the reception of the upper end of the chute, the side walls of the chute terminating a short distance from the upper end thereof, a wall formed in the plate opposite the end of one of the side walls of the chute for guiding a button into the chute as it moves along said wall, and an auxiliary plate covering the opening in said plate to assist in guiding the buttons into the chute, 95 said non-rotatable plate capable of being tilted upwardly to afford free access to the chute.

22. A button feeding mechanism comprising a chute, a plate pivotally mounted in relation thereto, a rotatable hopper casing on said plate, a portion of the upper part of the plate being dished, the said plate provided with an opening cut through the dished portion, the top surface of the chute lying in a plane parallel with the dished surface of the plate, and an auxiliary plate also extending along the upstanding wall of the dished portion so that as the hopper rotates buttons will drop within the chute and other buttons will slide along the dished portion to the bottom of the hopper, said first mentioned plate adapted to be tilted upwardly to remove any offending button from the 110 opening in the plate and the chute.

23. A feeding mechanism for button attaching machines comprising a chute, a plate pivotally mounted with relation to said chute, the said plate having an opening 125 therein for the reception of the upper end of said chute, the said plate being dished on the opposite sides of the opening, the upper surface of the chute merging with the dished surface of the plate, the side walls 130 of the chute being of such height at their

end as to receive a button which lies in a proper receiving position, a rotatable casing fitting on said plate and bodily removably therefrom, an arm extending from said plate 5 provided with pulleys and the casing having a groove around its periphery, and a belt received in said groove and pulleys adapted to rotate said casing, said plate 10 tilttable to remove an offending button from said chute.

24. A feeding mechanism for button attaching machines comprising a chute, a plate pivotally mounted at its upper end and co-operating with said chute, the plate provided with a circular platform, a rotatable hopper casing fitting over said platform and the height of the platform being such that it projects slightly above the bottom surface of the casing to thereby form a small 15 ledge for supporting the buttons as they are carried to the top of the platform, the plate provided with an opening for the reception of the upper end of the chute, the ledge in the platform being broken near the 20 opening in said plate to thus provide a guiding wall for the button into the chute, and means for rotating the hopper casing, said hopper casing being adapted to tilt 25 upwardly to afford free access to the chute,

25. In a button feeding mechanism, a chute, a non-rotatable plate mounted in pivotal relation to the chute, a rotatable hopper casing on said plate, a bottom rim 30 formed in the hopper casing having radial walls extending to a point near the inner portion of the rim, and a portion of the plate 35 extending slightly above the inner upper surface of the rim to form a ledge for supporting the buttons, the plate provided with an opening for the reception of the upper 40 end of the chute, the ledge being broken at the entrance of the chute to thereby permit a button to pass into the chute as the radial walls on the rim move away from a descending 45 button, and said plate capable of being swung upwardly to afford free access to the chute.

26. In a button feeding mechanism a support, a trough secured to said support, the upper end of the trough merging into an 50 arm, a bearing formed in said arm, a plate pivotally mounted in said bearing and having means formed thereon to enclose said trough when the plate is in its normal position, a chute formed in two sections in said 55 trough, said plate having an opening, the upper end of the upper section of the chute registering with the opening in said plate to thereby permit a button to pass into said chute, a rotatable hopper casing on said 60 plate, and means for rotating the hopper, said plate adapted to be raised to afford easy access to the chute without affecting the rotating means.

27. A feeding mechanism for button attaching machines comprising a chute, a rotatable hopper casing, and a bottom plate 65 fitting within the casing, the bottom plate provided with an opening for alignment with said chute and being movable independently of the rotatable movement of the hopper casing so that an offending button 70 may be removed from the chute.

28. A feeding mechanism for button attaching machines comprising a chute, a rotatable hopper casing, and a normally non-movable bottom plate for the casing, the bottom plate arranged with an opening for alignment with said chute and the plate and chute so arranged that the chute may be 80 exposed to view to remove an offending button from the chute.

29. A feeding mechanism for button attaching machines comprising a chute, a rotatable hopper casing, and a separate plate 85 forming a bottom for the casing normally covering said chute, the plate arranged with an opening to register with said chute, and the chute and plate arranged so that one of said parts may be swung to provide free 90 access to said chute.

In testimony whereof I affix my signature.

FORREST G. PURINTON.
